United States Patent

Des. 239,748

Patented May 4, 1976

239,748

TUBE HOLDER AND TUBE CAP THEREFOR

Malcolm Mellon and Ann Diaz, both of 22 Riverside
Drive, New York, N.Y. 10023

Filed Feb. 3, 1975, Ser. No. 546,529

Term of patent 14 years

Int. Cl. D23—02

U.S. CL. D6—87

FIG. 1.

FIG. 2.

FIG. 3.

FIG. 4.

FIG. 5.

FIG. 6.

FIG. 7.

FIG. 8.

FIG. 10.

FIG. 9.

FIG. 1 is a perspective view of a tube holder and tube cap therefor showing our new design, the tube cap being omitted for ease of illustration;

FIG. 2 is a side elevational view of FIG. 1, the side opposite being identical;

FIG. 3 is a front elevational view of FIG. 1;

FIG. 4 is a rear elevational view of FIG. 1;

FIG. 5 is a top plan view of FIG. 1;

FIG. 6 is a bottom plan view of FIG. 1;

FIG. 7 is a top perspective view of the tube cap with the holder omitted for ease of illustration;

FIG. 8 is a bottom perspective view of FIG. 7;

FIG. 9 is an exploded side elevational view of the tube holder and tube cap therefor; and

FIG. 10 is a bottom plan view of the tube cap inserted into the holder.

We claim:

The ornamental design for a tube holder and tube cap therefor, substantially as shown.
